UNITED STATES PATENT OFFICE.

JESSE A. B. SMITH, OF STAMFORD, CONNECTICUT, ASSIGNOR TO UNDERWOOD TYPEWRITER COMPANY, OF NEW YORK, N. Y., A CORPORATION OF DELAWARE.

TYPEWRITING-MACHINE.

1,349,109.

Specification of Letters Patent. Patented Aug. 10, 1920.

Application filed November 2, 1918. Serial No. 260,811.

To all whom it may concern:

Be it known that I, JESSE A. B. SMITH, a citizen of the United States, residing in Stamford, in the county of Fairfield and 5 State of Connecticut, have invented certain new and useful Improvements in Typewriting-Machines, of which the following is a specification.

This invention relates to typewriting machines in which plies of web are led into the machine for typing several copies simultaneously and tearing off sections when typed. It is found in practice that the drag of the webs upon the line-spacing 10 mechanism of the typewriting machine may sometimes lead to faulty results, especially if the line-spacing handle is operated suddenly. The feed rolls provided upon the typewriter are properly effective for use 15 with sheets of paper of ordinary length; but in some cases they may prove inefficient for unwinding the webs from the rolls or spools, especially where several very large rolls of paper are employed. These rolls have great 20 weight, and are not readily started into rapid rotation by the pull thereon of the webs as they are drawn forward by the platen and its feed rolls.

In my application No. 242,734, filed July 30 1, 1918, now Patent No. 1,288,720, granted Dec. 24, 1918, there is provided means for automatically unwinding webs from the rolls, so that no extra burden will be placed at any time upon the line-feeding rolls of 35 the typewriter. The object of the present invention is to provide a simple device for this purpose, and the invention is shown as applied to a typewriting machine of the class disclosed in the patent to Wernery & 40 Smith, No. 1,132,055.

In practising the present invention, the operator pulls the webs off from the rolls manually, preparatory to typing the page or form. This operation requires but little 45 attention from the operator, and the device is simple and readily applicable to existing machines. When the platen is thrown up to straighten out the webs, as in said Wernery & Smith patent, the operator pulls the sheets 50 forwardly and impales them upon one or more re-registering pins. While the sheets are held upon these pins, the operator pulls the sheets, pins and all forwardly to a certain point, which may be predetermined by 55 means of an adjustable gage. The operator

then shifts back the carbons independently of the web, to positions to coöperate with fresh portions of the webs, as set forth in said Wernery & Smith patent. During this carbon shifting, the work sheets or webs 60 are retained upon the re-registering pins at the position determined by said adjustable gage, as just explained. Thereupon the operator, by an additional manipulation, unwinds all the webs from the rolls. This is 65 done by pulling forward the webs together with the re-registering pins, as well as the carbons. This movement continues to an extent determined by a second adjustable gage. By this time enough of the webs 70 is paid off from the spools to furnish a supply for the next form, so that during the typing of said next form, the spools may remain stationary, and therefore do not have to be stirred by the line-spacing operation 75 of the typewriter. It will be understood that the carbons have been brought forward together with the webs during the unwinding operation; but this movement of the carbons is an idle one. The operator 80 now proceeds to carry back all of the sheets, including the webs and carbons, to position them preparatory to beginning the typing of the next form. The length of this return stroke is determined by a rear stop, 85 which the carbon-carriage strikes. Further advantage is gained by clamping webs together during this return stroke, and the operator at this time needs to pay no further attention to holding the sheet upon the 90 re-registering pins. After the carbon-carriage is thus returned for the second time, the webs will hang in loops from the spools, and these loops will be taken up during the succeeding line-spacing operations. 95

Other features and advantages will hereinafter appear.

In the accompanying drawings, Figure 1 is a fragmentary perspective view of a fan-fold Underwood typewriting 100 machine, showing my invention as applied thereto.

Fig. 2 is a perspective view of the pin slide seen from the back.

Fig. 3 is a sectional side view, largely 105 diagrammatic, showing the position of the work-sheets after a form has been typed or filled out with the platen thrown to its upper position and before the carbon sheets have been retracted.

Fig. 4 is a similar view showing the carbon sheets retracted.

Fig. 5 is a similar view showing the web advanced, having dragged the carbon sheets 5 along with it.

Fig. 6 is a similar view showing the webs as finally retracted by the carbon-sheet carriage just before swinging the platen to writing position.

10 Fig. 7 is a sectional side view of a stop for arresting the pin slide.

In the usual Underwood fan-fold typewriting machine of the type shown in the patent to Wernery & Smith, No. 1,132,055, 15 the typewriter carriage 10 slides along a rear rail 11 and a front rail, not shown, and has journaled therein a swing frame 12, in which is journaled a platen 13 adapted to form a writing support for the outer 20 web 14 and the inner webs 15. To enable the usual line-space handle 16 to advance the platen by the usual ratchet wheel 17, the stub axle 18 in the carriage, to which the ratchet wheel 17 is fast, is provided 25 with a gear wheel 19 which meshes with a pinion 20 fast on the shaft 21 about which the swing frame 12 turns. The axle of the platen 13 is provided with a gear wheel 22 identical with the gear wheel 19, with the 30 result that there is always a train of gearing between the line-space wheel 17 and the platen 13, irrespective of the position of the platen.

The typewriter carriage of such machines 35 is drawn along by the usual spring barrel, not shown, under the control of an escapement mechanism, not shown, so that types 23 may print upon the outer web or worksheet 14. Between the outer web 14 and 40 each of the webs 15, there is a carbon sheet 24. Said sheets 24 are supported usually upon the cross-bars 25 of a supplementary carriage 26, which is adapted to travel front- 45 wardly and rearwardly along the rails 27 of the rearward extension 28 of the typewriter carriage 10. The webs 14 and 15 are adapted to be drawn over the rear bar 29 of the extension 28 between side gages 30 and 31, and threaded between the cross-bars 25 50 which may extend alternately as usual from opposite sides beyond the center of the supplementary carriage 26. From here the webs are carried forwardly and downwardly over the paper table 33, and then under and 55 upwardly in front of the platen 13, where they pass up over a front paper table 34 provided with adjustable edge gages 35.

To write a form at the beginning of a day's work, the carbon sheets are properly 60 adjusted relatively to the form already printed on the web or webs 14 and 15, and then the desired entries are made. After 65 finishing the typewriting of the entries, the typist swings the typewriter platen 13 to the position seen in Fig. 3 by pressing rear-

wardly the hook 36 which normally holds the swing frame 12 against the feed rolls, not shown, and then drawing the handle 37 forwardly, with the result that the swing frame 12 rotates around the shaft 21 to the 70 Fig. 3 position. Before doing this, or else immediately after swinging the swing frame, the typist impales the openings 38 on the webs 14 and 15 upon pins 39 fast on a slide 40, so that when the platen 13 is 75 in the Fig. 3 position, the webs and the carbon sheets 24 will be positioned as shown in Fig. 3.

The typist then pushes the carbon-sheet carriage rearwardly to the Fig. 4 position 80 by means of the handle 43. The handle supports a finger-piece 41 which is adapted to operate a clamp 42, whose utility will appear later. The connections between the finger-piece 41 and the clamp 42 include a 85 link 44 pivoted to the finger-piece 41, so that, as the finger-piece swings rearwardly around its pivot 45 against the pressure of its spring 45, it will swing rearwardly a 90 rock-arm 46 to which the rear end of the link 44 is pivoted, thereby rocking the shaft 47 to which the rock-arm 46 is fast, so that the clamping member 48, forming a second arm on the shaft 47, may clamp the web against the cross-bar 49. 95

When the carbon sheets have been pushed rearwardly, as just described, the parts occupy the Fig. 4 position. The typist now grasps a handle 50, upstanding from the slide 40, and depresses a finger-piece 51 100 against the tension of a spring 52, so as to swing an L extension 53 of the finger-piece clear of the stop 54, thus enabling the typist to push the handle 50 along the support 55 carrying with it the pins 39 and 105 the webs impaled thereon. The typist pulls the handle 50 along until it reaches the Fig. 5 position, in which the slide 40 is arrested by a stop 55, said stop being so placed that, in moving from the Fig. 4 position to the 110 Fig. 5 position, the web measures by its advance the length of a single form printed thereon.

It will be observed that at the time of drawing the webs to the Fig. 5 position, the 115 webs are advanced the length of a single form printed thereon. It will be also observed that at the time of drawing the webs to the Fig. 5 position, the webs are unrolled from the rolls 57, 58 and 59, on 120 which they are wound. The typist then grasps the finger-piece 41 and clamps the webs against the cross-bar 49, and pushes rearwardly on the handle 43, thus carrying rearwardly the carbon sheets and the webs 125 bodily to such a position that, when the swing frame 12 is swung back into place, the knife 56 will stand exactly at the point at which it is desired to sever the webs. This produces the slack portions 60 shown 130

in Fig. 6, from which the webs may be drawn during the next operation of line spacing, while writing, without the strain of unwinding them from the rolls 57, 58 5 and 59.

When the webs and carbon sheets are in the Fig. 6 position, the typist swings back the swing frame 12 into the typewriter carriage to the Fig. 1 position, and then operates the usual handle 61 to operate the knife 56 to sever the webs, thus, as pointed out, severing the webs at exactly the proper point and clear of the carbon sheets. The stops 54 and 55, referred to above, are adjustable along the extension 55^a, being for this purpose provided with thumb screws 62 adapted to be screwed onto threaded extensions 63 which pass through an open slot 64 in said extension, and are provided 20 with heads 65 to engage the back of the extension.

In order to limit the backward movement of the carbon-paper carriage 26 in moving from the Fig. 5 position to the Fig. 6 position, so that the webs may be moved precisely the length of a form on the web, there is provided an adjustable stop 66 adapted to be set in any one of a plurality of openings 67, and against this the rear portion of 30 the carbon-paper carriage 26 is adapted to strike. The slide 40, on which the pins 39 are carried, it will be noted, usually travels between the stops 54 and 55 only, and, if a whole form has been used, is usually at the 35 Fig. 6 position when the platen is thrown back to the Fig. 1 position. Since the webs may jump rearwardly at the moment they are seized between the platen and the feed rolls 68 in settling down to the Fig. 1 position, the slot 64 extends down toward the platen beyond the stop 54, and the stop 54 may normally lie in the path of movement of the slide 40 when advancing the webs, instead of blocking the slide against being 45 drawn toward the platen. In order to prevent the stop 54 from turning in the slot, its shank may be flattened as at 69 to fit the slot. The slide 40 may be held true to the guide or support 55^a by slots 70 in U-shaped 50 supports 71 embracing the guide.

Variations may be resorted to within the scope of the invention, and portions of the improvements may be used without others.

Having thus described my invention, I 55 claim:

1. In a typewriting machine, the combination with a traveling carriage and a carbon-paper carriage slidable thereon, of a device upon which sheets are adapted to be 60 grasped, a platen, means along which said device may be moved relatively to the platen, and a stop for limiting said movement to enable the automatic measuring of sections of sheets thereby.

65 2. In a typewriting machine, the com-

bination with a traveling carriage and a platen thereon, of a knife for severing work-sheets, a paper table along which work-sheets may be extended, a device for grasping work-sheets while they are drawn along 70 the table, and a pair of settable stops to measure the length of a work-sheet to be severed by said knife.

3. In a typewriting machine, the combination with a traveling carriage and a 75 platen thereon, of a knife for severing work-sheets, a paper table along which work-sheets may be drawn and extended, a device for grasping work-sheets while they are drawn along the table, a movably 80 mounted carbon-paper carriage adapted to shift carbon paper relatively to the work-sheets but normally free to be drawn along by friction of the webs on the carbon paper, a stop to limit the amount that the work-sheets are drawn along, and a stop to limit 85 the return movement of the carbon-paper carriage.

4. In a typewriting machine, the combination with a traveling carriage and a 90 platen thereon, of a knife for severing work-sheets, a paper table along which work-sheets may be extended, a device for holding work-sheets while they are drawn along the table, a movably mounted carbon-paper carriage adapted to shift carbon paper relatively to the work-sheets but normally free to be drawn along by friction of the webs on the carbon paper, an adjustable stop to limit the amount that the work-sheets are drawn along, and an adjustable 95 stop to limit the return movement of the carbon-paper carriage.

5. In a typewriting machine, the combination with a traveling carriage and a platen 100 revolvably mounted thereon, of a device along which a work-sheet may be drawn, a member to which it may be grasped for so drawing it, a stop normally effective to arrest said member, means for enabling said 105 member to pass said stop, a second stop to arrest said member, and a knife for severing the work-sheets near the platen.

6. In a typewriting machine, the combination with a traveling carriage and a 110 platen thereon around which work-sheets are adapted to be passed, of a carbon-paper carriage adapted to support carbon paper and to adjust it relatively to the work-sheets, a member to which the work-sheets 115 may be grasped for drawing them past the platen, so that the friction of the carbon paper sheets upon the work-sheets will draw along the carbon-paper carriage, a stop for said member, and an adjustable stop for 120 said carbon-paper carriage when returned from the first-named stop.

7. The combination with a typewriting machine comprising a platen, of rolls for delivering perforated webs to said platen, 130

1 a pin slide in advance of the platen comprising pins on which said webs are adapted to be alined by their perforations, and stops for determining the length of movement of said slide to enable the webs to be advanced together a predetermined distance.

8. The combination with a typewriting machine comprising a platen, of rolls for delivering perforated webs to said platen, 10 a pin slide in advance of the platen comprising pins on which said webs are adapted to be alined by their perforations, stops for determining the length of movement of said slide to enable the webs to be advanced together a predetermined distance, and a knife adapted to sever the webs at a point determined by the position of the stop at the end of the advance movement of the slide.

9. The combination with a typewriting 20 machine comprising a platen, of rolls for delivering perforated webs to said platen, a pin slide in advance of the platen comprising pins on which said webs are adapted to be alined by their perforations, stops for determining the length of movement of said slide to enable the webs to be advanced together a predetermined distance, a clamp for holding the webs together when alined by the pins, and a guide along which said clamp is adapted to be moved to bring the webs to printing position.

10. The combination with a typewriting machine comprising a platen, of rolls for delivering perforated webs to said platen, 35 a pin slide in advance of the platen comprising pins on which said webs are adapted to be alined by their perforations, stops for determining the length of movement of said slide to enable the webs to be advanced together a predetermined distance, a knife adapted to sever the webs at a point determined by the position of the stop at the end of the advance movement of the slide, a clamp for holding the webs together when alined by the pins, and a guide along which said clamp is adapted to be moved to bring the webs to printing position to enable them to be severed by said knife and to create slack in the webs behind the platen.

50 11. The combination with a typewriting machine comprising a platen, of a web-holding device for holding perforated webs, a device for permitting the platen to be shifted to permit the webs to be drawn thereunder, 55 a slide comprising pins for alining the webs by their perforations, and stops for limiting the movement of said slide to enable the webs to be moved a predetermined distance.

12. The combination with a typewriting 60 machine comprising a platen, of a web-holding device for holding perforated webs, a device for permitting the platen to be shifted to permit the webs to be drawn thereunder, a slide comprising pins for alining the webs by their perforations, stops for limiting the

movement of said slide to enable the webs to be moved a predetermined distance, and a knife for severing the webs at a point determined by the stop limiting the advance of the slide.

70 13. The combination with a typewriting machine comprising a platen, of a web-holding device for holding perforated webs, a device for permitting the platen to be shifted to permit the webs to be drawn thereunder, 75 a slide comprising pins for alining the webs by their perforations, stops for limiting the movement of said slide to enable the webs to be moved a predetermined distance, and a clamp for holding the webs together after 80 being adjusted by the pins.

14. The combination with a typewriting machine comprising a platen, of a web-holding device for holding perforated webs, a device for permitting the platen to be shifted to permit the web to be drawn thereunder, 85 a slide comprising pins for alining the webs by their perforations, stops for limiting the movement of said slide to enable the webs to be moved a predetermined distance, a clamp for holding the webs together after being adjusted by the pins, and a carriage for said clamp comprising a finger-piece to enable the carriage to be pushed rearwardly to 90 produce a slack in the webs.

95 15. The combination with a platen, of a device for holding sheets alined when passed around the platen, stops settable to vary the travel of said device, and a handle for moving the sheets when held by said device.

100 16. The combination with a platen, of a device for holding sheets alined when passed around the platen, stops settable to vary the travel of said device, a handle for moving the sheets when held by said device, and a knife for severing the sheets when repositioned by said handle.

110 17. In a typewriting machine, the combination with a platen about which sheets are adapted to be passed, of a frame in which said platen is mounted to enable it to be shifted to enable the sheets to be straightened, a device for holding the sheets alined that are passed around the platen, stops settable to vary the travel of said 115 device, and a handle for moving the sheets when held by said device.

120 18. The combination with a platen about which perforated sheets are adapted to be passed, of a frame in which said platen is mounted to enable it to be shifted to enable the sheets to be straightened, a device comprising pins adapted to hold the sheets by the perforations, stops settable to vary the travel of said device, and a handle for moving the sheets when held by said device.

125 19. The combination with a platen about which perforated sheets are adapted to be passed, of a frame in which said platen is mounted to enable it to be shifted to enable 130

the sheets to be straightened, a device comprising pins adapted to hold the sheets by the perforations, stops settable to vary the travel of said device, a handle for moving the sheets when held by said device, and a knife for severing the sheets when repositioned by said handle.

20. In a typewriting machine, the combination with a platen about which sheets 10 are adapted to be passed, of a frame in which said platen is mounted to enable it to be shifted to enable the sheets to be straightened, a device for holding sheets alined that are passed around the platen, 15 stops settable to vary the travel of said device, a handle for moving the sheets when held by said device, and a stop settable to arrest the handle in repositioning the sheets.

21. The combination with a platen, of a 20 device for holding sheets alined when passed around the platen, stops settable to vary the travel of said device, a handle for moving the sheets when held by said device, and a stop settable to arrest the handle in repositioning the sheets.

22. The combination with a typewriting machine comprising a platen, of a web-holding device for holding perforated webs, a device for permitting the platen to be shifted to permit the webs to be drawn thereunder, a slide comprising pins for alining the webs by their perforations, stops for limiting the movement of said slide to enable the webs to be moved a predetermined 30 distance, a clamp for holding the webs together after being adjusted by the pins, a carriage for said clamp comprising a handle to enable the carriage to be pushed rearwardly to produce a slack in the webs, and 35 a stop settable to arrest the handle in repositioning the sheets.

23. The combination with a typewriting machine, of rolls adapted to deliver webs to said machine, a platen, a device against 45 which webs are adapted to be grasped to draw them from said rolls, and a traveling clamp adapted to clamp the webs together when so drawn, and then return the drawn-off section to create a slack between the 50 platen and the rolls.

24. The combination with a typewriting machine, of rolls adapted to deliver webs to said machine, a platen, a device against which webs are adapted to be grasped to draw them from said rolls, a stop for arresting said device, and a traveling clamp adapted to clamp the webs together when so drawn, and then to return the drawn-off section to create a slack between the platen 55 and the rolls.

25. The combination with a typewriting machine, of rolls adapted to deliver perforated webs to said machine, a platen, a device comprising pins on which webs are 65 adapted to be alined by their perforations

to hold them together while being drawn from the rolls, a stop for arresting said device, and a traveling clamp adapted to clamp the webs together when so drawn, and then to return the drawn-off section to create a slack between the platen and the rolls.

26. The combination with a typewriting machine, of rolls adapted to deliver webs to said machine, a platen, a device against which webs are adapted to be grasped to draw them from said rolls, a stop for arresting said device, a traveling clamp adapted to clamp the webs together when so drawn, and then to return the drawn-off section to create a slack between the platen and the rolls, and a stop for arresting the backward movement of the clamp when the proper line on the web arrives at the printing point.

27. The combination with a typewriting machine comprising a platen, of rolls for delivering perforated webs to said platen, a pin slide in advance of the platen comprising pins on which said webs are adapted to be alined by their perforations, stops for determining the length of movement of said 90 slide to enable the webs to be advanced together a predetermined distance, and a clamp adapted to seize said webs when fully advanced and to return them to create a slack between the platen and the rolls.

28. The combination with a typewriting machine comprising a platen, of rolls for delivering perforated webs to said platen, a pin slide in advance of the platen comprising pins on which said webs are adapted to 100 be alined by their perforations, stops for determining the length of movement of said slide to enable the webs to be advanced together a predetermined distance, a clamp for holding the webs together when alined 105 by the pins, a guide along which said clamp is adapted to be moved to bring the webs to printing position, and a clamp adapted to seize said webs when fully advanced and to return them to create a slack between the 110 platen and the rolls.

29. The combination with a typewriting machine comprising a platen, of a web-holding device for holding perforated webs, a device for permitting the platen to be shifted to permit the webs to be drawn thereunder, a slide comprising pins for alining the webs by their perforations, stops for limiting the movement of said slide to enable the webs to be moved a predetermined 120 distance, a clamp for holding the webs together after being adjusted by the pins, a carriage on which said clamp is mounted, and a stop for arresting the clamp when it has been pushed rearwardly to create a slack 125 between the web-holding device and the platen.

30. The combination with a typewriting machine, of rolls adapted to deliver webs to the machine, a platen about which the webs 130

8
may be passed, a device upon which the webs are adapted to be grasped, means along which said device may be moved relatively to the platen, and a clamp for moving the webs backwardly to create a slack between the rolls and the platen equal to the line-spacing movement in writing upon the web before it is again severed.

31. The combination with a typewriting machine, of rolls adapted to deliver webs to the machine, a platen about which the webs may be passed, a device upon which the webs are adapted to be grasped, means

along which said device may be moved relatively to the platen, a clamp for moving the webs backwardly to create a slack between the rolls and the platen equal to the line-spacing movement in writing upon the web before it is again severed, and stops for positioning the device and the clamp at the limits of their travel to enable the measuring of sections of the web.
